Atty.

UNITED STATES PATENT OFFICE.

FRANKLIN BENNETT, OF MARSHALLVILLE, OHIO, ASSIGNOR OF ONE-THIRD
TO LEMMAN S. ZIMMERMAN, OF SAME PLACE.

DRILLING-MACHINE.

SPECIFICATION forming part of Letters Patent No. 338,021, dated March 16, 1886.

Application filed November 12, 1884. Serial No. 147,697. (No model.)

To all whom it may concern:

Be it known that I, FRANKLIN BENNETT, a citizen of the United States, residing at Marshallville, in the county of Wayne and State of Ohio, have invented a new and useful Improvement in Hand-Drill Presses, of which the following is a specification.

My invention has relation to that class of hand-drill presses having a head-block through which the drill-stock and feeding-screw pass, and two hooks depending therefrom to hold the article to be drilled.

The object of my invention is to render such presses adjustable to different forms and positions of work, and to hold the drill rigidly in line while working.

My invention consists in the devices illustrated in the accompanying drawings, in which—

20 Figure 1 is an elevation of my improved hand-drill press, the left half being shown in central vertical section; Fig. 2, a vertical cross-section of the head-block at the line *xx*. Figs. 3 and 4 represent, respectively, end and 25 side elevations of the foot-pieces.

The head-block *A* has a vertical slot running lengthwise of it, on each side of which are channels *a a*. A nut, *B*, is carefully fitted to slide in the slot and channels, and is screwed 30 threaded to receive the feeding-screw *G*. This screw, driven by the hand-wheel *D*, is hollow, and contains the drill-shaft *E*, which is operated by the ratchet *F*. By this arrangement the drill is maintained at right angles to the 35 head-block *A*, but can be moved toward either end to adapt it to the position of the work. The hooks *G G* are linked at their upper ends into rings *h* on the ends of the headed rods *H*, which pass through and turn in the block *A*. 40 The link joint may, however, be omitted, if desired, and the hooks pass directly through the head-block. By this construction the hooks can be turned in any direction that the work may require.

45 To adapt the hooks to present a flat upper face and constitute the foundation for a table at a right angle with the drill, I provide the foot-pieces *I I*. These each consist of an independent plate having a plain upper face,

and on the under face two parallel flanges, the 50 distance between them being equal to the width of the hook, between which flanges is an inclined surface having the same angle as the hook. In use one of these plates is placed on each hook, the latter entering the space between 55 the flanges and resting on the inclined surface between them, the upper face of the plate being parallel with the lower face of the head-block *A*, thereby affording two plane surfaces upon which to place any article to be drilled. 60

I am aware that a head provided with rigid pendent hooks and having parallel ways and a nut fitted to slide in said ways and bearing a feeding-screw, between which and the article held by the hooks a ratchet-drill may be 65 placed, is not new, and this I do not claim. The objection to this arrangement is, that as the drill simply rests against the lower end of the feeding-screw, it has nothing to hold it in line or prevent it from deviating from the line 70 of the screw.

The advantage of my device is, that the feeding-screw itself affords a guide for the drill-shaft.

I claim—

1. The combination, with a head-block provided with hinged pendent hooks and having parallel ways and a nut fitting in said ways and arranged to slide therein, of a hollow feeding-screw fitting said nut, provided with 80 a hand-wheel and inclosing a drill shaft provided with driving mechanism, substantially as shown, and for the purpose hereinbefore set forth.

2. The combination, with a hook connected 85 with the head-block of a hand-drill press, of a plate, *I*, having two flanges, *i i*, with intermediate formation arranged to fit on said hook, substantially as shown, and for the purpose specified.

In testimony that I claim the foregoing I have hereunto set my hand this 13th day of September, A. D. 1884.

FRANKLIN BENNETT.
